[73] Assignee: Pitney Bowes Inc., Stamford, Conn.

[21] Appl. No.: 447,925

[57] ABSTRACT

[22] Filed: Dec. 8, 1982

A method and associated apparatus for controlling firmware branch points in an electronic postage meter, comprising the steps of storing a program for operation of the electronic postage meter, providing at least one data bit external to the stored program, each such data bit corresponding to a particular branch point in the program, and selecting a branch of the program for use in operation of the meter in accordance with the data bit so that the program may be readily reconfigured based on the presence of a data bit.

FIG. 4

CONTROLLING FIRMWARE BRANCH POINTS IN AN ELECTRONIC POSTAGE METER

CROSS REFERENCE TO RELATED APPLICATIONS

The present application is related to copending application Ser. No. 447,815, filed on Dec. 8, 1982 in the name of Danilo Buan, entitled STAND-ALONE ELECTRONIC MAILING MACHINE, now U.S. Pat. No. 4,579,054, which describes a postage meter within which the present invention may be utilized, and copending application Ser. No. 447,912, filed on Dec. 8, 1982 in the names of John H. Soderberg and Edward C. Duwel, entitled, MODIFYING A FIRMWARE VARIABLE IN AN ELECTRONIC POSTAGE METER, abandoned.

PROGRAM APPENDIX

A program listing for an electronic postage meter such as disclosed in the aforementioned related patent application of Danilo Buan is set forth as part of the specification at the end of the detailed description and before the claims.

BACKGROUND OF THE INVENTION

The present invention relates to electronic postage meters and more particularly, to electronic postage meters operating under control of a program and including non-volatile memories (NVMs), such as the type disclosed in the aforementioned related patent application.

Known electronic postage meter employing firmware such as disclosed in U.S. Pat. No. 4,301,507, issued on Nov. 17, 1981, and assigned to Pitney Bowes, Inc. of Stamford, Conn. are programmed via ROMs to undergo a certain sequence of operations. Such arrangement is adequate for use with a particular postal system such as that presently employed in the United States. However, for an electronic postage meter to be capable of international usage, where the requirements of the postal systems of the various countries vary widely, a number of individual programs or software packages tailored to the requirements of each country to accommodate such variations would increase the programming costs significantly. Further, even in the United States, it may be desirable to provide for external tripping of the meter for testing.

SUMMARY OF THE INVENTION

It is an object of the present invention to provide a program for an electronic postage meter which may be reconfigured for a particular application by information stored in the meter.

It is a further object of the present invention to provide a programmed electronic postage meter having a program which may be readily configured to satisfy a variety of postal systems.

It is a still further object of the present invention to provide an electronic postage meter having the same firmware for use in different postal systems.

It is a still further object of the present invention to provide a firmware controlled electronic postage meter for different applications in which programming costs are minimized.

Briefly, in accordance with the present invention, a method and apparatus for controlling firmware branch points in an electronic postage meter is provided comprising the steps of storing a program for operation of

the electronic postage meter, providing at least one data bit external to the stored program, each such data bit corresponding to a particular branch point in the program, and selecting a branch of the program for use in operation of the meter in accordance with the data bit so that the program may be readily reconfigured based on the presence of a data bit.

Other objects, aspects and advantages of the present invention will be apparent from the detailed description considered in conjunction with the preferred embodiment of the invention illustrated in the drawings, as follows:

BRIEF DESCRIPTION OF THE DRAWINGS

FIG. 1 is a block diagram of the generalized electronic circuit for a stand-alone electronic postage meter;

FIGS. 2A and 2B is a detailed block diagram of the electronic circuitry for a stand-alone electronic postage meter;

FIG. 3 is a flowchart for reconfiguring the firmware to provide for a remote trip; and

FIG. 4 is a flowchart for reconfiguring the firmware to reset the meter in accordance with its reset condition.

DETAILED DESCRIPTION

Referring to FIG. 1, the electronic postage meter includes an 8-bit microprocessor 10 (CPU), such as an Intel Model 8085A microprocessor which is connected to various components through a system bus 12. ROM 14 is connected to the microprocessor 10 through the system bus 12. The ROM 14 stores the programs for controlling the postage meter. It should be understood that the term ROM as used herein includes permanently programmed and reprogrammable devices. An integrated circuit 16, which may be Intel Model 8155, is connected to the system bus 12 and includes RAM, input and output lines and a timer. The RAM portion of the integrated circuit 16 has memory space allocated for transient storage of the data for the ascending register and descending register. An external data communication port 18 is connected to the microprocessor 10 through optical isolator 20. The external data communication port 18 allows connection with devices such as an electronic scale, an external computer, servicing equipment and the like. Also electrically connected to the microprocessor 10 through the system bus 12 is the keyboard 22 of the postage meter and a non-volatile memory (NVM) 24. Stepper motors 26, 28 are also in electrical connection with the microprocessor 10 via motor drivers 30 and the integrated circuit 16. A reset and power control 32 is electrically connected between the integrated circuit 16, the NVM 24 and the microprocessor 10. A relay 34 connects the AC printer motor 36 to the integrated circuit 16. A display 38 is also electrically connected to the integrated circuit 16. Trip photosensor 40 is connected to the microprocessor 10 through integrated circuit 16 to indicate the presence of an envelope to be stamped, as described more fully in the aforementioned patent application entitled, STAND-ALONE ELECTRONIC MAILING MACHINE.

The electronic postage meter is controlled by the microprocessor 10 operating under control of the programs stored in the ROM 14. The microprocessor 10 accepts information entered via the keyboard 22 or via the external communication port 18 from external message generators. Critical accounting data and other

important information is stored in the non-volatile memory 24. The non-volatile memory 24 may be an MNOS semiconductor type memory, a battery augmented CMOS memory, core memory, or other suitable non-volatile memory component. The non-volatile memory 24 stores critical postage meter data during periods when power is not applied to the postage meter. This data includes in addition to the serial number of the mailing machine or postage meter information as to the value in the descending register (the amount of postage available for printing), the value in the ascending register (the total amount of postage printed by the meter), and the value in the piece count register (the total number of cycles the meter has performed), as well as other types of data, such as trip status, initialization and service information, which are desired to be retained in the memory even though no power is applied to the meter.

When an on/off power switch 42 is turned on (closed) a power supply internal to the mailing machine energizes the microprocessor 10 and the balance of the electronic components. The information stored in the non-volatile memory 24 is transferred via the microprocessor 10 to the RAM of the integrated circuit 16. After power up the RAM contains an image or copy of the information stored in the non-volatile memory 24 prior to energization. During operation of the postage meter, certain of the data in the RAM is modified. Accordingly, when postage is printed, the descending register will be reduced by the value of the printed postage, the ascending register increased by the value of the printed postage and the piece counter register incremented. When the power switch 42 is turned off (opened), the updated data in the RAM is transferred via the microprocessor 10 back into a suitably prepared area of the non-volatile memory 24. A like transfer of information between the non-volatile memory 24 and the RAM takes place during power failure.

Referring to FIG. 2, a more detailed block diagram of the arrangement of the electrical components for the postage meter is illustrated generally as 48. Power is supplied to the postage meter from the AC line voltage, typically 115 volts. This line voltage is applied to the meter through a hot switch 50 which cuts off power to the postage meter to protect the electrical components thereof if the temperature rises above a preset limit, nominally 70° C. The hot switch 50 is connected to the AC drive motor 36A through an RF filter 52 and an opto-triac 54 which provides isolation between the line voltage and the control logic for the meter. The hot switch 50 is also connected to a transformer 56 protected by a fuse 58. The output of the transformer 56 is coupled to a pre-regulator 59 through a cold switch 60. The cold switch 60 cuts off power to the pre-regulator 59 if the temperature drops below a preset limit, nominally 0° C. The pre-regulator 59 provides an output voltage of a predetermined range to a switcher 62 which generates the output voltage +5 V; and the voltages for generating -12 V and -30 V.

The +5 V is applied to a +3 volt regulator 64 and then to the display 38A. The +5 V from the switcher 62 is also applied to a +5 V filter 66 which provides +5 V for logic circuits. Specifically, the +5 V is applied to the keyboard 22A, the display 38A, and bank, digit and trip sensor logic 68 and to the integrated circuits. The -12 V is applied to a -12 V regulator 70 and then to the non-volatile memory 24A.

The -30 V output from the switcher 62 is also applied to a -30 V regulator 74 and then to a -30 V switch 76 which switches its output voltage on and off

in response to the requirements of writing in NVM as dictated by the program. The output of the -30 V switch is applied to the non-volatile memory 24A. The -30 V supply is connected to the power on reset 72 of the microprocessor 10A.

+5 V from the switcher 62 is also supplied to one input of the power on reset 72; the other input receives -30 V from the regulator 74 as previously described. A low voltage sensor 88 also receives one input +5 V from the switcher 62 and its other input from the pre-regulator 59; its output is applied to the microprocessor 10A. The low voltage sensor 88 detects power failure and communicates this to the microprocessor 10A which in turn addresses the RAM through system bus 12A to transfer all security data present in the RAM to the non-volatile memory 24A.

Another output from the pre-regulator 59 in the form of +24 V is applied to the digit and bank motor drive 30A for the bank motor 26A and digit motor 28A, which selects the particular printing wheel (bank) which is to be activated and the particular digit of the selected printing wheel which is to be set.

An output strobe from the integrated circuit 16A is buffered through buffer drive 68 and applied to digit sensor (encoder) 78, bank sensor (encoder) 80, and trip sensor 40A. The opto strobe applies power to the digit sensor 78, bank sensor 80 and trip sensor 40A when needed. The output from the trip sensor 40A is applied to the input/output lines 82 which are coupled to the integrated circuit 16A. The outputs from the digit sensor 78 and bank sensor 80 and cycle switch 84 are applied to a storage buffer 86.

During power up, the key switch 42, see FIG. 1, is closed, and the AC line voltage energizes the electrical components previously described and an Initialization process will occur. Such initialization may include a hard and/soft initialization process as disclosed in the aforementioned U.S. Pat. No. 4,301,507. Preferably the Initialization process is that described in copending application Ser. No. 695,027, filed on Jan. 28, 1985 in the names of Alton B. Eckert and Easwaran C. N. Nambudiri entitled, Stand Alone Electronic Mailing Machine, now U.S. Pat No. 4,559,443, and assigned to the same assignee as the present invention.

In operation, the microprocessor 10A under control of the ROM 14A and possibly the auxiliary ROM 100 communicates over the address bus 94 and control bus 98 with the device select 98. The output of the device select 98 communicates with the particular module to be addressed over select lines 99. The modules to be addressed are the RAM, the ROM 14A, an auxiliary ROM 100, a demultiplexer 102, NVM logic 104 and the buffer 86 and optionally for testing external memory 106. The RAM of integrated circuit 16A provides the working memory for the postage meter and the microprocessor 10A. The ROM 14A stores the program; the auxiliary ROM 100 may be used to provide additional program storage space. The non-volatile memory 24A provides storage of all security information for the meter and retains such information during power down or power failure. The demultiplexer 102 latches the lower eight (8) bit of address information that defines a particular location which is used immediately thereafter. The NVM logic 104 controls the data applied to the NVM 24A and also provides ready wait and NVM ready signals to the micro-processor 10A to advise it to wait for the NVM 24A or that the NVM 24A is ready to receive data over the data bus 108.

As previously mentioned, the digital sensor 78 (opti-

cal encoder) and bank sensor 80, (optical encoder) and cycle switch 84 whose current state is read, i.e., "Home" or "In Cycle", apply input signals to the storage latch 86 which sends output signals over data bus 108 to the microprocessor 10A for storage in the proper RAM location.

The RAM is also electrically coupled to I/O lines to transmit or receive data from the trip sensor 40A, the display 38A, keyboard 22A, and privilege access switch 110, if present. The privilege access switch 110 may be used in applications which require manual resetting of meter postage via a switch which is kept under seal.

A program listing for a postage meter of the type described in the aforementioned related patent application of Danilo Baun is set forth in the Program Appendix. The flow charts discussed below indicate how one or more external data bits preferably stored in non-volatile memory can be used to reconfigure those portions of the active software (firmware) stored in one or more ROMs. The program listing includes the code for the flow chart in FIG. 3, but only a portion of the code for the flow chart in FIG. 4.

Referring to FIG. 3, the flow chart for effecting an external trip via an external communication channel, e.g., the external test point (TP) shown in FIG. 2, is illustrated as 110. A special bit for providing an EXTERNAL TRIP is stored (written) into the non-volatile memory during manufacture. In performing the EXTERNAL TRIP, the meter status is checked to determine if the KEYBOARD is disabled. If it is not disabled, this subroutine returns error status to the superordinate process and no trip occurs. If the KEYBOARD is disabled, the meter status is again checked to see if it is enabled. If not, error status is returned to the superordinate process. If meter status indicates enabled (MRSTS1.ENAB) is TRUE, we access certain addresses in the non-volatile memory (NVM) to see if the serial number lock (NVM.SERLCK) is TRUE. That is, a specific bit is accessed in the non-volatile memory to determine whether the serial number of the postage meter has been locked in non-volatile memory. If it has not, the trip is executed and normal status is returned to the superordinate process. However, if the serial number has been locked in the non-volatile memory, another address in the non-volatile memory is accessed to determine whether a bit is present to disable the external trip. If so, error status is returned to the superordinate process. However, if a trip lock (NVM.TRPLCK) bit has not been set in a non-volatile memory, a trip is executed. Thereafter, control is returned to the superordinate process with normal status.

Referring to FIG. 4, at the end of entry, the Reset Routine illustrated as 120 occurs after the meter has been primed for reset by entry of combination and amount messages. Initially, it is determined whether the meter is in a service state. If so, the service function is executed and control is returned to the superordinate process. If the meter is not in a service state, the meter status is checked to determine if it is in the privileged state, i.e., the privilege switch for manual postage resetting is operable. Reset in this case is accomplished with a privileged access switch under either wire/metal seal, paper seal, or keylock (same for all meters). With this method "monies" are entered directly into the descending register when the privileged access switch is in the "on" position, i.e., in the privileged state. If it is in the privileged state, a non-volatile memory address NVM.UNIT is accessed to determine if the unit is a meter that has single or double register. If a single regis-

ter, it is cleared to zero and control is returned to the superordinate process. If the unit is a double register, a further address in a non-volatile memory is accessed to determine if the double register meter is reset via a manual combination NVM.RESET or a non-combination reset. After the reset, control is returned to the superordinate process. If NVM.RESET is set, a manual combination reset is executed and if NVM.RESET is not set a non-combination manual reset is executed. Control is then returned to the superordinate process.

Upon reading the state of the meter, if it is determined that it is not in a privilege state, an address in the non-volatile memory is accessed to determine if the value in NVM.UNIT is set to indicate the unit is a double register meter. If it is not set, a procedural error is declared and control is returned to the superordinate process. If it is set to indicate a double register meter, the values are equal and a variable remote meter resetting (VRMRS) is executed and control is returned to the superordinate process.

Thus, it is apparent that the branching resulting from the EXTERNAL TRIP and RESET routines is dependent upon the presence or absence of certain bits in non-volatile memory.

More details regarding the privilege switch, VRMRS and manual reset (combinational or non-combinational) and the routines therefore can be obtained from U.S. Pat. No. 4,301,507, issued on Nov. 17, 1981, and assigned to Pitney Bowes, Inc. of Stamford, Conn.

The functions illustrated in FIGS. 3 and 4 are illustrative of the present invention. It should be understood that the present invention may be utilized to control firmware branch points in an electronic postage meter to accomplish other functions such as, presetting of the registers and ascending register lockout. Preferably, as disclosed in the copending patent applications Ser. No. 355,437, filed on Mar. 8, 1982, in the names of Edward C. Duwel and John H. Soderberg, entitled, NON-VOLATILE MEMORY SERIAL NUMBER LOCK FOR ELECTRONIC POSTAGE METER, and Ser. No. 347,398, filed on July 12, 1982, in the names of Raymond R. Crowley and John H. Soderberg, entitled, ELECTRONIC POSTAGE METER HAVING A ONE TIME ACTUABLE OPERATING PROGRAM TO ENABLE SETTING OF CRITICAL ACCOUNTING REGISTERS TO PREDETERMINED VALUES, after the serial number is set in the meter a "one time" program locks up the meter to preclude further changes therein.

It is known and understood for the purpose of the present application that the term postage meter refers to the general class of device for the imprinting of a defined unit value for governmental or private carrier delivery of parcels, envelopes or other like application for unit value printing. Thus, although the term postage meter is utilized, it is both known and employed in the trade as a general term for devices utilized in conjunction with services other than those exclusively employed by governmental postage and tax services. For example, private, parcel and freight services purchase and employ such meters as a means to provide unit value printing and accounting for individual parcels.

It should be apparent to those skilled in the art that various modifications may be made in the present invention without departing from the spirit and scope thereof as described in the specification and defined in the appended claims.

7468 ; A. Jones, Jr. and Frank T. Check, Jr. This patent is hereby
7469 ; incorporated by reference into the subject patent application.
7470 ; ****
7471 ;
7472 ; THIS IS THE DEMO PROGRAM FOR 6 STEPS/DIGIT MECHANISM
7473 ; USED FOR 45 DEG ENCODER & 30 DEG SENSOR MOUNTING
7474 ; Objective
7475 ; Position the stepper motor through specified number of steps.
7476 ; Flag the errors if
7477 ;      1. the move fails
7478 ;      2. if the sensors are not in home position
7479 ;         after the completion of a move
7480 ; Level:
7481 ; Calls RENC , BKFLASH routines
7482 ; utilizes look up table setup for determining the step count
7483 ; requirements for retries.
7484 ; Exits with the power held on to both motors. It is the duty of the
7485 ; invoking routine to judiciously hold the appropriate home phase.
7486 ; Procedure MOVCLS(MOTOR,RETRIES,MCOUNT,SPEED:ERROR)
7487 ; ERROR := 0
7488 ; Input (PORT1.SENSOR,SESPIN)
7489 ; SESPIN := SENSPTN and MSNMASK

What is claimed is:

1. Apparatus for controlling the firmware branch points in an electronic postage meter comprising:

ROM means for storing a program for the electronic postage meter, said program including at least one firmware branch point wherein a different part of the program for meter operation is accessed in accordance with each branch from the branch point;

non-volatile memory means having addresses therein for storage of information;

said non-volatile memory means having at least one specified address wherein for storing a selectable data bit;

said data bit corresponding to selection of a particular active branch of the program at said firmware branch point; and

means interconnecting said ROM means and said non-volatile memory means for providing communication therebetween to control the firmware branch point to cause access to the branch of the program selected in accordance with the data bit present in said non-volatile memory means.

2. The apparatus in claim 1 wherein said interconnecting means includes a system bus and a microprocessor.

3. The apparatus of claim 1 wherein there are a plurality of data bits stored in said non-volatile memory means, each data bit being operative for controlling branching at an associated firmware branch point of the program, said data bits thereby providing a selected configuration of active branches of the program.

4. The apparatus of claim 1 wherein the presence of said data bit controls the branching at a firmware

branch point to select a branch which includes remote tripping of the postage meter.

5. The apparatus of claim 1 wherein the presence of said data bit controls the branching at a firmware point to select a branch which includes resetting of the postage meter.

6. The apparatus of claim 1 wherein the presence of said data bit controls the branching at a firmware branch point to select a branch which includes presetting of the postage meter.

7. The apparatus of claim 1 wherein the presence of said data bit controls the branching at a firmware branch point to select a branch which includes locking out the ascending register.

8. Apparatus for controlling the firmware branch points in an electronic postage meter, comprising:

ROM means for storing a program for the electronic postage meter, said program including a plurality of firmware branch points wherein a different part of the meter operating program is accessed in accordance with each branch from the branch points; a non-volatile memory having addresses therein for storage of information; said non-volatile memory including a selected plurality of data bits stored in specified addresses of said non-volatile memory;

25 each of said data bits respectively corresponding to a

particular branch of the program desired to be active; and

5 interconnecting means including a microprocessor and a system bus for interconnecting said ROM means and said non-volatile memory for providing communication therebetween to control the firmware branch points of the program in accordance with the selected data bits present in said non-volatile memory.

10 9. A method of controlling the firmware branch points in an electronic postage meter comprising the steps of:

15 storing a program for operation of the electronic postage meter in at least one ROM, said program including at least one firmware branch point wherein a different part of the program for meter operation is accessed in accordance with each branch from the branch point;

20 selectively storing at least one data bit within a non-volatile memory of the postage meter; and selecting a predetermined branch of the program for use in operation of the meter whenever said data bit is stored within the non-volatile memory, whereby the firmware branch point is controlled by the presence of the data bit stored in non-volatile memory.
